UNITED STATES PATENT OFFICE.

ALFONSO SORIENTE, OF BROOKLYN, NEW YORK.

CANE CONSTRUCTION.

Application filed April 3, 1928. Serial No. 266,890.

The main object of this invention is to provide a cane which is so constructed as to give a maximum amount of rigidity and still be somewhat flexible so that it may not 5 be easily broken.

Another object of this invention is to provide a two piece cane consisting of handle and a staff, the staff being secured to the handle, and the entire length of the staff 10 has its surfaces covered with inlays of woods.

The above and other objects will become apparent in the description below, in which characters of reference refer to like-named 15 parts in the drawing.

Referring briefly to the drawing, Figure 1 is a broken longitudinal elevational view of the cane.

Figure 2 is an enlarged cross sectional 20 view taken on line 2—2 of Figure 1.

Figure 3 is a cross sectional view through the handle of the cane taken on line 3—3 of Figure 1.

Figure 4 is a longitudinal sectional elevational view through the upper portion of 25 the cane showing a modified type of handle.

Referring in detail to the drawing, the numeral 10 indicates a longitudinal staff of uniform diameter throughout its length and 30 circular in cross section. One end of this staff has a sleeve 11 secured thereto which is fixed to the staff by passing a pin 12 through the staff and the sleeve. The extremity of the sleeve is sealed by a hemispherical solid peg 13 and is of some suitable hard material which will wear well, 35 as said peg is constantly brought into contact with the pavement. The opposite end 14 of the staff is inserted into a bore formed 40 in a substantially semi-circular handle 15 whose free end merges into a point 16. The sides of this handle have curved channels formed therein in which curved strips of inlay 17 are inserted.

45 At spaced-apart positions along the length of the staff a plurality of rings 18 are positioned. It is to be noted that the sleeve 11 which is secured to one end of the staff is mounted in place as the last member. Before the first ring is mounted in 50 place, wide longitudinal strips of inlay 19 are glued to the circumferential surfaces of the staff and these wide strips are separated from narrower strips 20 by exceedingly 55 narrow strips 21. A ring is then inserted over the staff, then shorter strips 22, of the

same widths as the strips 19, 20 and 21, are mounted on the opposite side of the ring, then an additional ring 23 is slipped over the staff, and this building up continues until the surface of the entire staff is covered by a layer of inlay. The ends of the strips 19, 20, 21 and 22 have converging, inclined edges 24 which engage similarly formed edges 25 formed in the rings 18 and 23. 60 65

The construction illustrated in Figure 4 is identical to the construction used in the cane of Figure 1 but presents a modification in the handle 26 which is of angularly extending bulbous formation which may be 70 conveniently gripped in the clenched palm of the hand.

The construction of the cane is such that no warping of the strips will result as is often the case in inlay articles with the 75 present process of manufacture. The rings 18 and 23 are of solid and unitary material, turned on a lathe or other desirable machine out of solid material, such as ivory or wood. It is to be noted that these strips and rings 80

are to be of different colors so that a definite contrast between inlays may be had, that is, the rings 18 and 23 and the strips 21 should be properly of a darker or a lighter color than the strips 19 and 20 which should be 85 provided with a color giving a contrast to the remaining members surfacing the staff. As a cane becomes aged the glue, which causes the inlay to adhere to the circumferential surface of the staff, will become 90 soft, owing to the moisture content in the air seeping into these places where the glue is provided, and the ends of the strips 19 and 20 would, with an ordinary construction, warp and bend upwardly. This is not possible with the construction shown in the 95 drawings as it will be noted the end edges of the rings 18 and 23, together with the end edges of the strips 19, 20 and 21, are inclined or tapered so that the strips 19, 20 and 21 100 dove-tail the edges of the rings and, in this manner, the edges of said strips are securely locked over the rings and will be prevented from lifting as in warping.

The uses of the cane are obvious, and a description will not be attempted as it is ordinarily an article of dress or an aid to incapacitated persons.

It is to be noted that certain changes in form and construction may be made without 110 departing from the spirit and scope of the invention.

I claim:

1. A cane comprising a longitudinal staff, a handle surmounting one end of said staff, inlay covering said staff comprising longitudinal strips of various widths and contrasting colors, rings slipped over said staff, said strips and said rings alternating throughout the length of said staff, said rings having inclined edges converging toward the axis of said rings, and means on the edges of said strips contacting with said inclined edges of said rings to prevent warping of said strips.
- 10 2. A cane comprising a longitudinal staff,

a handle surmounting one end of said staff, 15 inlay covering said staff comprising longitudinal strips of various widths and contrasting colors, rings slipped over said staff, said strips and said rings having inclined edges converging toward the axis of said rings, said strips and said rings alternating throughout the length of said staff, said strips having inclined edges dove-tailing with the inclined edges of the rings to prevent warping of said strips.

20 25 In testimony whereof I affix my signature.

ALFONSO SORIENTE.
